UNITED STATES PATENT OFFICE.

BERTIE R. HALL, OF OUTLOOK, SASKATCHEWAN, CANADA.

VACUUM-CLEANER.

1,216,229.

Specification of Letters Patent. Patented Feb. 13, 1917.

Application filed November 29, 1915. Serial No. 64,192.

To all whom it may concern:

Be it known that I, BERTIE R. HALL, a citizen of the United States, residing at Outlook, in the Province of Saskatchewan and Dominion of Canada, have invented new and useful Improvements in Vacuum-Cleaners, of which the following is a specification.

This invention relates to improvements in 10 vacuum cleaners, and particularly to hand operated cleaners.

The primary object of the invention is to construct a hand operated vacuum cleaner which shall be simple, cheap and thoroughly 15 efficient.

With the above and other objects in view, the improvement resides in the construction, combination and arrangement of parts set forth in the following specification and falling 20 within the scope of the appended claim.

In the drawing:

Figure 1 is a side elevation of a vacuum cleaner constructed in accordance with the present invention.

Fig. 2 is a central vertical longitudinal sectional view through the same, and

Fig. 3 is a perspective view looking toward the underface of the fan casing, illustrating the manner in which the headed end 30 of the pipe section is secured to the casing and the handle member being broken away.

Referring now to the drawing in detail, the numeral 1 designates the suction or dirt pipe, and 2 a substantially rectangular nozzle arranged upon the lower end thereof. The pipe 1 preferably has its upper end provided with a head in the shape of a flat disk 3, and this disk is surrounded by the annular flange 4 of a fan casing 5. The periphery of 40 the disk is spaced a suitable distance from the inner periphery of the flange 4 and the casing 5 is sustained upon the pipe by a plurality of radially disposed arms 6 which connect with the lower edge of the flange 4 and secured upon the pipe 1 below the disk 3 thereof. Secured centrally to the outer and closed top of the fan casing 5 is a handle member 7, and arranged upon the said handle are shafts 8 and 9. Mounted for rotation upon the shaft 8 is a toothed wheel 10, the same having a crank handle 11 and this wheel meshes with a spur gear 12 arranged upon a beveled tooth wheel 13 journaled upon the shaft 9. The wheel 13 55 meshes with a pinion 14 disposed in the slot

or recess in the handle 7, the said pinion being provided upon one end of a shaft 15 which passes through the top of the fan casing 5 and which is connected with the blades 60 of the fan 16.

By this arrangement the train of gears will revolve the fan 16 rapidly so that the same will suck the dirt through the nozzle 2 and pipe 1 and below the fan over the disk 3 through the space or opening 17 between 65 the flange 4 of the fan casing and the periphery of the said disk 3.

The numeral 18 designates the dirt bag. This bag is provided upon its lower end with an opening just sufficient to receive the 70 pipe 1, the said opening being preferably provided by an extension or neck 19, and a tying element, such as a cord 20, is wound around the neck 19 to bind the same against the pipe 1. The upper and open end of the 75 bag 18 is likewise secured by a cord 21 to the flange 4 of the fan casing.

From the above description, taken in connection with the accompanying drawings, it will be noted that I have provided an extremely simple, cheap and reliable vacuum cleaner and it is thought that the simplicity thereof as well as the method of operation will be appreciated by those skilled in the art to which such invention appertains without further detailed description, it being merely necessary to add that by releasing the cord 21, the dirt may be removed from the bag 18.

Having thus described the invention, what I claim is:

The herein described construction of vacuum cleaners including a nozzle having a pipe connected therewith and said pipe having its end provided with a head in the shape 95 of a flat disk, a fan casing surrounding the disk and spaced therefrom, radially disposed arms secured to the edge of the fan casing and connected with the pipe, a fan within the casing, a handle supported by the casing, 100 said casing and pipe adapted to receive the opposite ends of a dirt bag, and operating mechanism upon the handle for the fan.

In testimony whereof I affix my signature in presence of two witnesses.

BERTIE R. HALL.
